United States Patent Office

Des. 225,616
Patented Dec. 26, 1972

225,616

BOTTLE

Bjorn Bagn, New Hartford, Conn., assignor to Emhart
Corporation, Bloomfield, Conn.

Filed Sept. 3, 1970, Ser. No. 24,823

Term of patent 14 years

Int. Cl. D9—01

U.S. Cl. D9—12

FIG. 1

FIG. 2

FIG. 1 is an elevational view of a bottle showing my new design; and

FIG. 2 is an enlarged fragmentary sectional view showing the bottom portion thereof.

The side opposite that seen in FIG. 1 is the same in appearance as the side shown and the bottle is circular in all horizontal cross sections.

I claim:

The ornamental design for a bottle, as shown and described.
